UNITED STATES PATENT OFFICE.

ARTHUR F. FRITZ, OF CANASTOTA, NEW YORK.

SWING.

1,264,172.

Specification of Letters Patent. Patented Apr. 30, 1918.

Application filed February 27, 1917. Serial No. 151,340.

To all whom it may concern:

Be it known that I, ARTHUR F. FRITZ, a citizen of the United States, residing at Canastota, in the county of Madison and 5 State of New York, have invented certain new and useful Improvements in Swings, of which the following is a specification.

This invention relates to improvements in swing devices, more particularly to the 10 class of lawn swings, and has for one of its objects to improve the construction and increase the efficiency and utility of devices of this character.

Another object of the invention is to provide a device of this character capable of 15 seating one or more persons and wherein provision is made for enabling the occupants of the seats to cause the swing to operate by pressure applied to a system of levers.

With these and other objects in view, the invention consists in certain novel features of construction, as hereinafter shown and described and then specifically pointed out 25 in the claim; and in the drawings illustrative of the preferred embodiment of the invention.

Figure 1 is a perspective view of the improved device.

Fig. 2 is a side elevation with the "head" 30 portion of the supporting frame in longitudinal section.

Fig. 3 is an end elevation with the head portion of the supporting frame in trans- 35 verse section.

Corresponding and like parts are referred to in the following description and indicated in all the views of the drawings by the same reference characters.

The improved device comprises a supporting frame including a head or body formed 40 of side members 10-11 disposed in spaced relation and provided at the ends with spaced blocks 12-13. The supporting portion of the device likewise includes leg members 14 coupled to the terminals of the head members 10-11 by strap devices 15. The leg members 14 are disposed obliquely to the longitudinal plane of the head member 50 so that at their lower ends the leg members are spread apart, as shown in Fig. 1, to insure the stability of the supporting structure. The leg members are arranged in pairs, and connected respectively by trans-

verse brace members 16. The legs are likewise reinforced by obliquely directed brace members 17, bolted at their ends to the leg members, and likewise coupled at their crossing points by bolts 18. At the junctions of the brace members 16 and leg members 14 brace blocks 19 are inserted and secured by bolts or like devices.

By this means a very stiff and rigid supporting frame is produced which will hold the head portion of the device firmly in position and prevent its displacement laterally or longitudinally.

Pivoted at 20 between the side members 10-11 is the main swing supporting stock or bar 21. Bearing upon opposite sides of 70 the lower end of the member 21 are seat supporting rails 22, the rails being bolted or otherwise secured rigidly to the member 21 and further supported by spaced blocks 23 and brace devices 23'. Attached to the 75 outer portions of the members 22 are seats 24 each having a supporting back 25, the latter extending at its lower end to a line level with the lower faces of the members 22 and bearing against the ends of the same, 80 as shown in Figs. 1 and 2. Depending from the rail members 21 near each of the seats is a hanger 26 with the lower ends outturned as shown at 27, and supporting foot rest rails 28 to which a plurality of slats 29 are 85 secured. The members 26, 28 and 29 thus form an effectual foot rest for the occupants of the seat.

Mounted to swing at 36 upon each side of the member 21 are bars or levers 30 having transverse handles 31 secured to their ends, the handle members being within convenient reach of the occupants of the seats.

Pivoted at 32 between the side members 10-11 of the head portion of the device is 95 another bar 33 extending in parallel relation to the member 21 and pivoted at 34 between the lever members 30. The member 33 is spaced a considerable distance from the member 21 as shown more particularly, in Fig. 2. 100 The head members 10-11 and suspension member 21 and the lever device 33 are preferably of wood, and suitable metal wear plates indicated at 35, are applied to the members 21-33 where they extend between the members 10-11 and between the members 30, to prevent undue friction between the wood members. The members 22 are

likewise of wood, while the bracket devices 23' and of metal.

The improved device is designed more particularly for the use of children, and it will be obvious that when the seats are occupied the handles 31 are in convenient position to be grasped by the hand, and by forcibly depressing or elevating the handles a leverage action will be produced between the members 21 and 33 to cause the member 21 to swing upon its pivot 20 and thus produce the swinging motion, and the greater the force applied to the handles and the lever members 30 the greater will be the swinging movement. After the motion has been produced it may be maintained indefinitely by the exercise of relatively light force upon the handles.

The foot rest members 29 enable the occupant of the seat to secure the necessary bracing by the feet to apply the requisite force to the handles and the lever member 30.

Having thus described the invention, what is claimed as new is—

In a swing, a support, a suspension member swinging from said support, rails rigidly connected to the opposite faces of said suspension member and extending laterally therefrom, seats carried by the rails and extending transversely thereof and unobstructed beyond the rails, lever members pivoted intermediate their ends to the opposite faces of said suspension member, grip bars connected intermediate their ends to said lever members and extending in parallel relation to the longitudinal planes of the seats, an operating bar pivoted respectively to the levers and to the support and spaced from the suspension member, and foot rests supported from the rails and extending laterally beyond the vertical planes of the same.

In testimony whereof I affix my signature,

ARTHUR F. FRITZ. [L. S.]
